UNITED STATES PATENT OFFICE.

SERENO J. RAMSAY, OF ALGONA, IOWA.

DISPENSING AND DISPLAY CONTAINER.

Application filed July 14, 1924. Serial No. 725,944.

To all whom it may concern:

Be it known that I, SERENO J. RAMSAY, a citizen of the United States, residing at Algona, in the county of Kossuth and State 5 of Iowa, have invented new and useful Improvements in Dispensing and Display Containers, of which the following is a specification.

This invention relates to containers for 10 holding bulk candies, nuts, or similar commodities.

The object is to provide a container which will hold a relatively large quantity of such goods for dispensing purposes concealed 15 from the view and out of the reach of the purchaser, and having a relatively small quantity or thin layer arranged at the front of the container and along the top thereof in covering relation so as to give the impression that the container is completely 20 full, the front and top layers commingling at the front corner so as to enhance this effect.

Another object is to provide a container 25 for this purpose which may be placed as a unit within an ordinary show case, along with other similar containers, to entirely fill the same from end to end, thus showing a continuous array or series of apparently 30 full bins or hoppers containing nuts, candies of different kinds and colors, and providing an attractive advertising medium to catch the eye of the purchaser upon entering the store.

35 A further object is to provide a container which may be readily cleansed and kept in sanitary condition, the front display layer being protected from contact with the glass or other parts of the show case, and the top display layer being removable to fill the main receptacle when necessary by withdrawing the container from the show case without disturbing the other units.

40 A final object is to provide a dispensing and display container for bulk candy or the like which, while arranged in a show case, may have any desired quantity removed therefrom, at the rear of the same, without danger of any of the contents rolling out 45 upon the bottom of the show case, the rear of the container being designed for the reception of the usual scoop or shovel used for this purpose.

50 A full and complete understanding of the invention may be obtained from a consideration of the following detailed description,

taken in connection with the accompanying drawings forming a part of this specification, it being understood that while the drawings show a practical form of the invention, the latter is not to be confined to strict conformity with the showing thereof, but may be changed or modified, so long as such changes or modifications mark no material departure from the salient features of the invention, as specifically pointed out in the appended claims.

In the drawings in which similar reference characters designate corresponding parts throughout the several figures:—

Figure 1 is a perspective view of a show case having a series of the improved containers arranged in position on the bottom thereof.

Figure 2 is an enlarged detail perspective view of one of the containers.

Figure 3 is a vertical, longitudinal section through the container.

Figure 4 is a vertical, transverse section taken on the line 4—4 of Figure 3.

Figure 5 is a rear elevation of the device.

Referring to the drawings, there is shown a rectangular, box-like structure formed of suitable sheet metal, preferably a heavy grade of tin, and comprising a bottom 1 somewhat longer than wide, and opposite, upstanding side walls 2 extending from the front edge to the rear edge of the said bottom. The sides may be of any desired height and are preferably secured along 50 their bottom edges to the sides of the bottom by extending the margins of the latter downwardly and thence inwardly, as at 3, and forming the lower edges of the sides into inwardly extending foot portions 4 and 55 crimping the margins of the same over the margins of the bottom, as clearly shown in Figures 4 and 5 of the drawings. The foot portions 4 serve to elevate the bottom 1 above the floor of a show case or other support, and serve as runners to slide the container into and out of position between other units of its kind, when a plurality of containers are placed in a show case, as illustrated in Figure 1.

The front edge of the bottom 1 is turned upwardly to form a flange 5, and the front edges of the sides 2 are turned inwardly to form side flanges 6, to form abutments for a front glass or other suitable transparent 110 panel 7 extending from the bottom 1 to the top of the sides and contacting with the

latter so as to expose the entire front of the device to view.

Spaced somewhat in rear of the glass front 7 is a sheet metal partition 8, extending transversely between the sides 2 and parallel to the said front, the lower edge of the partition being turned rearwardly to form an attaching flange 9 which may be soldered or otherwise secured to the bottom, 10 while the upper edge of the partition, which is somewhat below the top edges of the sides 2, is bent to the rear to form a horizontal, transverse support 10, the marginal portion of the same being then bent downwardly to 15 form a hand hold 11 for a purpose to be explained, all of which is clearly shown in Figure 3.

The side margins of the partition 8 are extended forwardly to constitute attaching 20 portions 12 which are suitably fastened, preferably by soldering, to the front portions of the side plates 2, and the front margins of said extensions are directed inwardly 25 towards each other to form inner abutment flanges 13 for the glass front and to retain the same in position. An inverted channel strip 14 surrounds the upper edge of the glass front and protects the same from accidental breakage and also serves to protect 30 the hands of the operator, the ends of said strip being suitably secured, as by soldering, to the upper, front corners of the sides 2.

The sheet of metal comprising the bottom 1 is initially cut somewhat longer than the 35 sides 2, and the excess portion located at the rear of the container is bent upwardly to form a lower rear wall 15 flush with the lower rear edges of the sides 2, and the marginal portion of the metal is then bent downwardly and forwardly to form an inclined 40 chute 16, the lower, front edge of which rests upon the bottom and is preferably soldered thereto to prevent ingress of water into the cavity thus formed during the process of 45 washing or cleansing the container.

A transverse strip of sheet metal 17 has its ends soldered or otherwise secured between the upper, rear portions of the sides 2 to 50 form an upper rear wall, which is preferably inwardly set from the rear edges of said sides, the said strip having its lower portion 18 bent inwardly in substantial parallelism to the lower, inclined wall or chute 16, and forming therewith, an opening for the 55 purpose of shoveling or scooping out the candy or other contents, when the same is being retailed.

The upper edge of the transverse strip 17 is bent forwardly to form a rear, horizontal, 60 transverse support 19 in substantial alinement with the front support 10, the marginal portion 20 being then bent downwardly to avoid injuring the hands of the operator.

65 The supports 10 and 19 respectively are

adapted to support a combined cover and display tray 21, which fits snugly between the upper edges of the sides 2 while resting upon said supports, and which is adapted to be removed for the purpose of filling the 70 receptacle or container. The tray 21 is also adapted to carry a relatively thin layer of the candy, nuts, or other goods or confections to be dispensed from the container proper, said layer completely filling the tray. 75 The space between the partition 8 and the front glass plate 7 constitutes a pocket 22, and is also adapted to be filled and at the point where the pocket and the tray join, the contents will commingle and give the appearance of a completely filled bin or hopper, even though the supply in the container proper may be nearly exhausted.

The sides of the tray 21 are provided with upstanding, shallow walls 23, and the rear edge of the tray is turned upwardly and returned upon itself to form a rear wall 24, while the metal constituting the bottom of the tray 21 is extended forwardly, at its 80 front edge, and curved downwardly as at 25 to form an overhanging lip extending into the upper portion of the aforesaid pocket 22, the terminal portion of said metal being again returned upon itself and extended rearwardly and thence bent at right angles to form a flange 26 beneath the bottom of the tray 21, and perpendicular thereto, for the purpose of engaging the aforesaid front support 10 to serve in properly 85 positioning the tray and to prevent any longitudinal movement of the same. The upstanding sides 23 of the tray being located between the upper edges of the sides 2 of the container prevents any lateral movement of said tray.

With the tray removed, a quantity of the goods to be dispensed may be readily poured or placed into the container through the open top thereof, the inclined wall 18 serving to prevent any of the goods from passing out through the outlet 27, for the goods are caused to assume an inclined position, as indicated in dotted lines at the lower edge of the said wall 18, where they are in convenient position to be shoveled or scooped out in the ordinary manner. As the bulk of the goods above this point is lowered, the same will maintain this position at the outlet opening, and there is no danger of the same 100 rolling out.

The pocket 22 is filled up to the top and, prior to placing the filled tray in position, the container proper is placed in position in the show case, as shown in Figure 1, by supporting the front end of said container with the fingers of one hand placed beneath the depending flange or hand hold 11; while the fingers of the other hand may engage beneath the lower rear wall 15 or the lower 110 edge of the inclined wall 18. This manner 120

of handling the container will avoid disturbing the displayed candies, etc. in adjoining containers. The tray is now filled and placed in position on the container, and by placing a small quantity at the top of the pocket, a thin layer is provided across the top and down the front to give the desired appearance of a full box. The contents of the tray and the pocket may be readily changed at any time for fresh material, and the same may be freely dispensed from the rear of the container even down to the last portion thereof. The restricted outlet at the back of the container serves to preserve the contents in good condition, by excluding the light and the heat and preventing the ingress of dust and dirt.

From the foregoing it will be seen that a simple, cheaply manufactured, and strong and durable container has been provided, which freely permits of the dispensing of all of the contents thereof, while preserving the same in a clean and fresh condition; that the display feature thereof gives at all times the appearance of a completely filled container, thus adding to its attractiveness and aiding in the sales, and that the device has the added advantage of being easily cleansed, handled, re-charged, and placed in position in a show case or elsewhere.

What is claimed is:—

1. A dispensing and display container for bulk candy or the like comprising a main receptacle having an outlet at the rear thereof, and provided with a pocket having a transparent front wall and located at the front of the receptacle, a separate tray forming the top of the main receptacle and removable therefrom to permit filling the same, said tray and said pocket being adapted to hold candy or the like independently of the main receptacle, said tray having its bottom wall at the front supported on the inner wall of the pocket and having its front end open and communicating with the top of the pocket to cause the candy in each to commingle and give the appearance of a full receptacle at all times.

2. A dispensing and display container for bulk candy or the like comprising a main receptacle having an outlet at the rear thereof, and provided with a pocket having a transparent front wall and located at the front of the receptacle, a separate tray forming the top of the main receptacle and removable therefrom to permit filling the same, said tray and said pocket being adapted to hold candy or the like independently of the main receptacle, said tray comprising a bottom wall adapted to rest at its front

end on the upper edge of the rear wall of the pocket, and having a rear wall and side walls and a down-turned front wall extending within the pocket to permit the candy in the tray to commingle with the candy in the pocket, so as to give the appearance of a full container at all times.

3. A dispensing and display container for bulk candy or the like comprising a main receptacle including a bottom and side walls, a transparent wall secured at the front edges of the same, a vertical partition wall secured in rear of and spaced from the transparent wall to form a vertical pocket, a rear wall joining the bottom and sides and provided with an outlet opening elevated above the bottom and extending from side to side, a forwardly and downwardly inclined chute extending from the lower edge of the outlet opening to the bottom of the receptacle, a similarly inclined chute extending from the upper edge of said outlet opening, said rear wall and partition wall terminating short of the upper edges of the main side walls, and a tray adapted to rest on the upper edges of the rear and partition walls to form a top to the main receptacle and removable to permit filling the same, said tray having upstanding side and rear walls flush at their upper edges with the sides of the receptacle and a down-turned flange at its front edge to fit over the partition, said pocket and tray being adapted to be filled with candy or the like.

4. A dispensing and display container for bulk candy or the like comprising a main receptacle including a bottom and side walls, a transparent wall secured at the front edges of the same, a vertical partition wall secured in rear of and spaced from the transparent wall to form a vertical pocket, a rear wall joining the bottom and sides and provided with an outlet opening elevated above the bottom and extending from side to side, a forwardly and downwardly inclined chute extending from the lower edge of the outlet opening to the bottom of the receptacle, a similarly inclined chute extending from the upper edge of said outlet opening, said rear wall and partition wall terminating short of the upper edges of the main side walls, and a tray adapted to rest on the upper edges of the rear and partition walls to form a top to the main receptacle and removable to permit filling the same.

In testimony that I claim the foregoing as my own, I have hereto affixed my signature.

SERENO J. RAMSAY.
